Attorney.

UNITED STATES PATENT OFFICE.

FRANK A. McDONALD AND FERDINAND G. WELKE, OF SAN FRANCISCO, CALIFORNIA.

CLOSURE-CAP LOCK.

Application filed January 21, 1926. Serial No. 22,816.

This invention relates to closure caps and locking means therefor, and it provides a device which is particularly useful in connection with tanks carrying inflammable material, such, for example, as gasoline tanks mounted on automobile trucks.

An object of this invention is the provision of an efficient and quickly operable lock for a closure cap.

Another object is the provision of means for attaching to a device of the character mentioned, a grounding lead to discharge static electricity from a tank containing inflammable material and from the closure cap thereof.

With the foregoing objects in view, together with such other objects and advantages as may subsequently appear, this invention resides in the construction and arrangement of parts hereinafter described and claimed, and illustrated in the accompanying drawings, in which

Figure 1 is a plan view of our device.

Figure 2 is a cylindrical, longitudinal section of the device shown in Figure 1.

Figure 3 is a vertical section taken on the line 3—3 of Figure 2.

Figure 4 is an elevational view of a member employed in our device for holding one end to a wire which may be grounded to discharge static electricity from the device.

Figure 5 is an elevational view of a split ring employed in our device and associated with a tubular member shown in cross section.

Figure 6 is a section taken on line 6—6 of Figure 2.

Figure 7 is a central, longitudinal section of the tubular member shown in cross section within the split ring in Figure 5.

The device of our invention comprises a cylindrical, tubular body 9, having an internally threaded upper portion 10 and an externally threaded reduced lower end portion 11, which is intended to be screwed to a tank. A screw cap 12 threadedly engages the upper portion 10 of the tubular body 9. The screw cap 12 is provided with opposing radial handles 13 for the purpose of facilitating the placement and removal of the cap relative to the tubular member 9. The screw cap 12 is provided with a lateral aperture 15, shown in Figures 2 and 3.

A tubular member 16 is integral with the tubular member 9 and extends laterally therefrom, the interior of the tubular mem-

ber 16 being continuous with an aperture formed in the side of the tubular member 9, this latter aperture being continuous with the aperture 15 formed in the cap. 60

A bolt 18 is provided in our device to lock the cap 12 to the tubular member 9 by passing through the aperture 15 in the cap and an opposing aperture inside of the tubular member 9. 65

The locking bolt 18 comprises a reduced inner end portion 19, an outwardly tapering portion 20, extending outwardly from the reduced portion 19.

A fixed sleeve 22 is disposed within the 70 tubular member 16 and encircles the locking bolt 18. The sleeve 22 functions as an abutment for one end of a coiled spring 23, the other end of which presses against an annular shoulder 24 formed on the locking bolt 18. 75

The coiled spring thereby functions to exert pressure on the locking bolt, urging it inwardly into position for locking the cap 12 to the tubular member 9. The locking bolt 18 is prevented from rotating by a pin 80 27 which passes through an aperture 28 formed in the bolt, and has its ends embedded in the walls of the tubular member 16.

The slot 28 has a greater length, lengthwise of the bolt, than the diameter of the pin 27, allowing the bolt 18 to be retracted from locking position. The outer end of the locking bolt 18 is externally threaded and threadedly engages a rotatable, tubular member 29, shown in Figures 2 and 7. 85

The tubular member 29 extends outwardly beyond the tubular member 16, and its outer end portion is encircled by a rotatable member 30, having a knob 31. The rotatable member 30 is secured to the tubular member 29 by means of a pin 32. A washer 33, which may be of brass, is affixed to the outer end of the tubular member 16. 95

A split ring 35, shown in Figures 2 and 5, 100 abuts against the outer face of the washer 33. Each half of the split ring 35 has an inwardly extending lug 36, which projects into one of two apertures 37 formed in the tubular member 29. The split ring 35 fits 105 into and is secured in a recess 40 formed in a ring 41 of a member 42, which has a projection 43 extending upwardly from the ring.

The member 42 encircles the tubular member 29, which passes through the aperture 45 in the member 42. An electrical con-

ductor 50 has one of its ends soldered in the recess 44, while its other end is permanently grounded, as indicated at 51.

In the operation of the device, a turning 5 of the knob 31 is effective to cause the locking bolt 18 to slide either into or out of locking position.

It is intended that the electrical conductor 50 shall be permanently grounded at a bulk 10 filling station, or in other words at a station at which the tank is to be filled. The parts associated with the conductor 50 also remain at the bulk filling station, and act as a key to unlock the cap of the tank. The 15 parts associated with the conductor 50 include members 30, 42, 35 and 29. When the tank is to be filled the parts associated with the conductor 50 must be employed in order to unlock the cap of the tank and in employing them, the static electricity from the tank 20 is discharged to the ground. It will, therefore, be readily appreciated that our device compels a person to discharge static electricity from the tank before opening the cap at 25 the filling aperture. Such provision in our device eliminates the more or less frequent accidents which follow the discharge of electricity in the presence of air and a fuel vapor, such for example as gasoline.

30 While we have described one embodiment of our invention, modifications thereof may be readily devised without departing from the spirit of our invention, and it is to be understood that such modifications come 35 within the scope of the appended claims.

We claim:—

1. In a device of the character described, a first tubular member adapted to be attached to a container, a removable cap for 40 closing the opening in said first tubular member, a second tubular member extending from said first tubular member, a non-rotat-

able slidable bolt in said second tubular member, said first tubular member and said cap being adapted to receive an end 45 portion, of said bolt, resilient means normally pressing said bolt into locking engagement with said cap and said first tubular member, said bolt being threaded, a key having a threaded end portion adapted 50 to threadedly engage said bolt and having a shoulder adapted to abut against the end of said second tubular member, a ring rotatably encircling said key and held thereto and an electrical conductor secured to said ring at 55 one end and grounded at its other end.

2. In a device of the character described, a first tubular member adapted to be attached to a container, a removable cap for closing the opening in said first tubular 60 member, a second tubular member extending from said first tubular member, a slidable bolt in said second tubular member, said first tubular member and said cap being adapted to receive an end portion of said bolt, resilient means normally pressing said bolt into locking engagement with said cap and said first tubular member, said bolt having a transverse aperture therethru, a pin passing thru the aperture and of smaller diameter than the aperture to permit the bolt to slide lengthwise in said second tubular member, said bolt being threaded externally, a key having an internally threaded end portion for threadedly engaging said bolt and 75 having a shoulder adapted to abut against the end of said second tubular member, said shoulder comprising a first ring secured to said key and a second ring held by said first ring to said key, said second ring being 80 adapted to have a grounding conductor secured thereto.
